UNITED STATES PATENT OFFICE.

ALBERT L. CLAPP, OF MARBLEHEAD, MASSACHUSETTS, ASSIGNOR TO THE FLINTKOTE COMPANY, OF BOSTON, MASSACHUSETTS, A CORPORATION OF MASSACHUSETTS.

CORNER BEAD AND METHOD OF MAKING THE SAME.

Application filed October 2, 1919. Serial No. 328,079.

To all whom it may concern:

Be it known that I, ALBERT L. CLAPP, a citizen of the United States, residing at Marblehead, in the county of Essex and 5 State of Massachusetts, have invented new and useful Improvements in Corner Beads and Methods of Making the Same, of which the following is a specification.

This invention has for its object to provide 10 a novel corner bead and a method of making the same.

In accordance with the invention, the corner bead is made of molded waterproof fiber, the rib being stiff and unyielding, so 15 as to preserve the line of the corner, and the wings being preferably more or less flexible so as to accommodate inequalities in the surfaces against which they are secured.

On the accompanying drawings,—

20 Figure 1 represents a portion of a blank from which the corner bead is to be produced.

Figure 2 represents the same after it has 25 been striped with a coating of waterproof adhesive material, and crushed mineral has been more or less embedded in the coating.

Figure 3 represents conventionally a section on the line 3—3 of Figure 2.

Figure 4 represents a section through the 30 molding devices, and illustrates how the corner bead is formed by molding.

Figure 5 illustrates a finished corner bead.

As the starting material, I employ a fairly 35 thick sheet of fibrous material containing an appreciable quantity of asphalt or equivalent waterproofing stiffening compound, which is rendered plastic by heat, but which, under normal atmospheric conditions, is relatively hard and stiff. For example, I may 40 use a paper felt, such as is employed in the manufacture of prepared roofing, and saturate or impregnate it with a high-melting-point asphalt or pitch or equivalent waterproofing compound, while such compound is 45 heated to a liquid state, or else I preferably employ a like paper felt but in which the asphalt of relatively high melting point is incorporated by any approved process, in the initial formation of the sheet. In the last- 50 mentioned case, the contained asphalt or pitch is caused to coalesce when the sheet is subjected to a sufficient degree of heat or to high pressure.

In Figure 1 there is illustrated a sheet of

asphalt—or pitch-containing material, which 55 is preferably cut in lengths of say six to ten feet and about five inches (more or less) wide. The middle of the strip is preferably coated with a longitudinal stripe *b* of high-melting-point pitch or asphalt, in which 60 is partially embedded a facing *c* of crushed or powdered slate, grit or other mineral material. Both faces of the strip *a* may be thus striped and faced. The strip thus formed is now ready for molding into final form as 65 a corner bead. Any suitable molding apparatus may be employed. I have shown a mold consisting of four elements or sections, namely a bottom section *6* being triangular in cross section, side sections *7, 7*, and a top 70 section *8*. The strip is folded along a median longitudinal line and placed on the section *6*, and the two side sections *7, 7*, are moved towards each other and the section *6*, after which the top section *8* is forced 75 downwardly. The resulting product is a corner bead having the side wings or attaching members *d, d*, the corner rib *e*, and the bead or enlargement *f* at the outer edge of the rib. The sections *7, 7*, of the mold 80 have faces *10, 10*, which force the side portions of the folded strip against the sides of the section *6*, but at *9, 9*, they have parallel faces, at an obtuse angle to the faces *10, 10*, which have the effect of folding the strip 85 into the rib *e*. Said sections *7, 7*, have the segmental concave faces *11, 11*, which co-operate with the semi-cylindrical groove or concave face *12* in the top mold, in forming the bead *f* at the edge of the rib. The pressure of the mold sections is sufficient not 90 only to compact the wings *d, d*, but to crowd the contacting portions of the rib together with such pressure that they form practically a solid mass, the asphalt or pitch in and on 95 the surface of the material coalescing. The grit or sand, which constituted the facing, is solidly embedded in the pitch or asphalt, and imparts inflexibility and rigidity to the 100 rib and bead.

Under some circumstances, the asphalt coating and grit facing may cover the entire face of the strip, but I prefer that the stripe formed on the initial strip shall be wide enough to include only those parallel zones 105 of the strip which subsequently constitute the rib and the bead, as I regard it as desirable that the wings of the finished article

should have a limited flexibility. The rib is inflexible and rigid, and its surface is more or less rough owing to the embedded sand and grit. The article is inexpensive in construction and is durable, not having the infirmities of the usual metal corner bead, since it is waterproof and is not affected by moisture and dampness. Of course, if desired, both the rib and the wings may be formed with the usual holes or openings to permit the keying of the plaster.

Having thus explained the nature of my said invention and described a way of making and using the same, although without attempting to set forth all of the forms in which it may be made or all of the modes of its use, what I claim is:—

1. A corner bead consisting of a waterproof fibrous material containing a waterproof stiffening material and having a rigid rib, and an attaching wing angular thereto.

2. A corner bead consisting of a molded fibrous material containing asphalt, and comprising a thick substantially rigid integral rib, and thinner and more flexible wings or attaching portions extending from said rib at an angle thereto.

3. A corner bead consisting of a fibrous material impregnated with a bituminous stiffening compound, and comprising a substantially rigid rib and semi-flexible wings or attaching portions.

4. A corner bead consisting of asphalt-containing fibrous material and comprising a rigid rib and more flexible attaching means angular to said rib.

5. A corner bead comprising a rib and angular attaching wings, said bead consisting of asphalt-containing fibrous material, and said rib being provided with a material for ensuring its rigidity.

6. A corner bead comprising a rib and attaching wings, said bead consisting of asphalt-containing fibrous material, and said

rib having a granular material embedded therein for increasing its rigidity.

7. A corner bead comprising a rib and attaching wings, said bead consisting of asphalt-containing fibrous material, and said rib having an external layer of asphalt with a mineral material embedded therein.

8. A corner bead comprising a rib and attaching wings, said bead consisting of a molded strip of asphalt-containing fibrous material, and said rib containing a stiffening material.

9. A corner bead comprising a rib and attaching wings, said bead consisting of a strip of asphalt-containing fibrous material, said rib being compacted and containing a stiffening material.

10. A corner bead comprising a rib and angular attaching wings, said bead comprising a strip of asphalt-containing fibrous material doubled substantially on its median line to constitute said rib and with its marginal portions at an angle to constitute said wings, said rib being united and compacted to substantially rigid condition.

11. The herein described method of making corner beads which consists in doubling a fibrous material containing a waterproof stiffening compound on a longitudinal line, and by pressure molding said doubled portions to form a unitary rib and divergent wings.

12. The herein described method of making corner beads which consists in applying a median strip of asphalt to a strip of fibrous material containing a waterproof plastic compound, embedding a stiffening material in said strip, doubling said strip on a median line, and by pressure molding said doubled portion to form a unitary rib and divergent wings.

In testimony whereof I have affixed my signature.

ALBERT L. CLAPP.
